[57] CLAIM

The ornamental design for a rotator primarily for a barbecue spit including an electrical adaptor therefor, as shown and described.

DESCRIPTION

FIG. 1 is a front elevational view of a rotator primarily for a barbecue spit including an electrical adaptor therefor;

FIG. 2 is a top plan view thereof;

FIG. 3 is a side elevational view thereof;

FIG. 4 is a rear elevational view thereof;

FIG. 5 is a bottom plan view thereof;

FIG. 6 is an elevational view of the side opposite that shown in FIG. 3;

FIG. 7 is a bottom plan view of the rotator and adaptor disconnected.

FIG. 1.

FIG. 2.

FIG. 3.

FIG 4

FIG 5.

FIG 6.

FIG. 7
